J. J. LANE.

VALVE.

APPLICATION FILED MAR. 20, 1916.

1,225,974.

Patented May 15, 1917.

Inventor,
John J. Lane.

By Balfour & Chenebattys.

UNITED STATES PATENT OFFICE.

JOHN J. LANE, OF ST. LOUIS, MISSOURI.

VALVE.

1,225,974.

Specification of Letters Patent. Patented May 15, 1917.

Application filed March 20, 1916. Serial No. 85,846.

To all whom it may concern:

Be it known that I, JOHN J. LANE, a citizen of the United States, residing at St. Louis, Missouri, have invented a certain new and useful Improvement in Valves, of which the following is a full, clear, and exact description, such as will enable others skilled in the art to which it appertains to make and use the same.

10 This invention relates to valves, and more particularly to packless valves, namely, valves of the type in which no stuffing box or other packing is necessary for preventing leakage around the valve stem.

15 One object of my invention is to provide a valve of the type referred to which comprises fewer parts than valves of this general type heretofore in use.

Another object is to provide a packless 20 valve in which the valve stem and casing are provided with coöperating conical surfaces, and a spring that tends to keep said surfaces in intimate engagement is arranged above said surfaces so that the medium that 25 passes through the valve will not come in contact with said spring and tend to deteriorate the same.

Another object is to provide a packless 30 valve in which threads on the valve stem co-operate with internal threads formed directly in the valve disk, so as to cause said valve disk to move vertically upwardly or downwardly to open or close the valve, whenever the valve stem is rotated.

35 A still further object is to provide a valve of the character described in which the pressure of the medium passing through the valve is utilized to prevent leakage around the valve stem. Other objects and desirable 40 features of my invention will be hereinafter pointed out.

The figure of the drawings is a vertical sectional view of a valve constructed in accordance with my invention.

45 Referring to the drawing which illustrates the preferred form of my invention, A designates the casing of the valve, B designates the valve disk and C designates the bonnet. The valve disk B herein shown 50 comprises a portion 1 that is adapted to co-operate with the seat 2 in the casing A, and an upwardly-extending portion 3 that is provided with laterally-projecting wings or lugs 4 that coöperate with vertical guides 5 in the bonnet C, so as to prevent said disk B from rotating, said portion 3 being pro-

vided with an internal screw thread 6 that coöperates with an externally screw-threaded portion 7 of the valve stem D. The valve disk B and its coöperating seat are herein 55 shown as applied to an ordinary globe valve, but I wish it to be understood that my invention is not limited to a valve of this particular type, as it is obvious that my invention is equally applicable to various other 60 types of valves. The stem D is provided intermediate its ends with a conical portion 8 that coöperates with a correspondingly shaped seat 9 formed in the bonnet C, said bonnet being provided with a pocket 10 65 above the conical seat 9 in which is arranged a coiled expansion spring 11 that lies between a shoulder 12 formed by the bottom of the pocket 10, and a removable abutment 13 carried by said stem. The pocket 10 is 70 circular in cross section and the abutment 13 is provided with a circular portion that fits snugly in the upper end of said pocket, said abutment being provided with a squared central bore that fits on a correspondingly-shaped portion 14 on the stem 75 D. The hand wheel 15 for rotating the stem bears directly against said abutment, and a nut 16 arranged above said wheel on a screw-threaded portion 17 of the stem D, 80 acts to prevent said abutment from moving vertically with respect to the stem when the valve is in service.

When the valve is in its open position, as shown in the drawing, the medium passing 85 through the valve is free to enter the inside of the bonnet C and exerts upward pressure on the base of the conical portion 8, thus keeping said conical portion pressed tightly against its seat 9 independently of 90 the spring 11 and preventing leakage around the valve stem.

Under ordinary service the coöperating 95 conical surfaces 8 and 9 are fully adequate to prevent leakage around the valve stem D, but to take care of unusual conditions, such as when a small particle of foreign matter becomes lodged between said surfaces and thus prevents said surfaces from engaging each other intimately, I have provided additional means for preventing leakage. This means consists of a washer 18 of rubber or other suitable resilient material that lies in the base of the pocket 10 and upon which the lower end of the spring 11 rests, the pressure 105 exerted by said spring acting to spread said washer and cause the same to engage the 110

stem tightly, and thus prevent leakage between the bonnet and valve stem at the point where said washer engages the same.

In the event that the washer 18 should become worn to such an extent that the same is unserviceable in an emergency, I have provided the removable abutment 13 and the pocket 10 of the bonnet C with alining annular grooves 19 in which suitable packing 10 may be inserted temporarily until such a time when the coöperating conical surfaces 8 and 9 can be cleaned or reground. The precise method of introducing packing into the grooves 19 is immaterial, but I have found in 15 practice that a strip of yielding packing material laid in the groove 19 of the abutment 13, when said abutment is separated from the pocket 10, can be easily forced down the side wall of said pocket when replacing the 20 abutment, said packing expanding into the groove 19 of the pocket 10 as soon as said grooves aline.

It is obvious that the removable abutment 13 could be made integral with the hand wheel 15 without departing from the spirit 25 of my invention, said abutment being made from a separate piece of metal merely for economy of manufacture.

From the foregoing it will be seen that I 30 have devised a valve which is very simple in construction; in which the valve stem is formed of a single piece, instead of the usual two telescoping parts, and threaded directly into the valve member proper, thus eliminating 35 several parts in the construction of my valve; in which no screw-threaded cap piece is necessary on the upper end of the bonnet; and in which all of the parts comprising the valve are of simple, rugged design that are 40 not likely to get out of order and which can be produced at a low cost of manufacture. The spring 11 need not be as large or strong as is ordinarily used in valves of this general type, as its only function in my valve is to 45 keep the conical surfaces 8 and 9 in engagement with each other when the valve is closed, or just starting to open, for when the valve is fully open, the pressure of the medium passing therethrough keeps said sur-

faces tightly together and prevents leakage 50 at this point.

The valve can be taken apart for inspection or repair easily and quickly by simply unscrewing the bonnet C from the valve body or casing A, and thereafter removing 55 the single nut 16 on the upper end of the valve stem D.

Having thus described my invention, what I claim, and desire to secure by Letters Patent, is:

A valve, comprising a casing provided with a valve seat, a valve disk that coöperates with said seat and which is provided with an upwardly-extending boss, said boss having an internally-screw-threaded bore 65 and a plurality of laterally-projecting lugs or wings, a bonnet arranged on said casing and provided with guideways that coöperate with said lugs, said bonnet being also provided with a conical portion, a one-piece 70 valve stem having a threaded portion that coöperates with the threaded bore in said valve disk and also a conical shoulder that coöperates with the conical portion of said 75 bonnet so as to prevent leakage around said valve stem and out of the upper end of said bonnet, said bonnet having a cylindrical pocket that surrounds said valve stem above 80 said conical portion, a resilient washer in the base of said pocket, an abutment carried by said valve stem and lying partly within said pocket, said abutment and pocket being provided with alining grooves for the reception of packing material, and a coiled expansion spring interposed between said 85 abutment and said washer, said spring exerting pressure on said washer so as to expand the same and cause it to tightly engage the valve stem and prevent leakage around same in case the first-mentioned leak-preventing means becomes inefficient.

In testimony whereof I hereunto affix my signature in the presence of two witnesses, this seventeenth day of March, 1916.

JOHN J. LANE.
